UNITED STATES PATENT OFFICE.

REUBEN C. DAYTON, OF RHINELANDER, WISCONSIN.

GAGE-TABLE.

972,101.

Specification of Letters Patent.

Patented Oct. 4, 1910.

Application filed August 28, 1909, Serial No. 515,022. Renewed August 20, 1910. Serial No. 578,242.

To all whom it may concern:

Be it known that I, REUBEN C. DAYTON, residing at Rhinelander, in the county of Oneida and State of Wisconsin, have invented certain new and useful Improvements in Gage-Tables, of which the following is a specification.

This invention is a gage table for use in connection with veneer clipping or cutting machines or the like, and the invention primarily has for its object to provide a gage table whereby the clipper operator may cut the veneers to such dimensions as desired with the minimum effort and maximum accuracy.

As now practiced in the art it is customary to use a wooden table having a slatted top onto which the veneer projects from the clipping machine. A yard stick or other measuring instrument is used to measure the width of the veneer that projects beyond the cutter onto the table, so that a strip of the desired width may be clipped off. In the trade, veneers are bought and sold according to their dry dimensions, that is, their dimensions after they have been dried and seasoned. The veneers when clipped have been directly cut from hot boiled or steamed logs and are saturated with water. A large shrinkage takes place in the process of drying and in order that the veneers when cut shall come up to the desired "dry" dimensions, the clipper operator must make an allowance for the shrinkage. The percentage of shrinkage varies with the different woods and the locality and climate in which the timber grew, so that when an order is placed with the clipper operator to be cut out, the shrinkage has to be figured on each different width and enough added so that the pieces when dried shall be of the required width. This process entails a large amount of clerical work in figuring shrinkages with constant liability of errors.

My invention therefore has for its object to provide a gage table wherein means are provided to set the veneer strip with respect to the veneer clipper, so that when cut and dried it will be of the required dimensions; and to so provide a gage table of the character stated that the changing, from one width to another, of the mechanism may be made by a nonskilled operator with absolute accuracy.

More specifically the invention provides a pair of butting blocks slideable in unison

over the table and against which the veneer strip engages, and the provision of a gage whereon the shrinkage is allowed so that the scale will read in feet, inches and fractions of inches directly but with the required correction for shrinkage. Means are also provided so that the butting blocks may be operated from one side and moved to any desired position, while another means is provided for limiting the movement of the blocks in a given direction when it is desired to change their position for any purpose so that when the blocks are again moved back to their original position it will be unnecessary for the operator to again consult the scale.

Sometimes it is necessary to trim stock after drying and allowance must be made therefor.

My invention also has for its object to provide means whereby the gage may be so adjusted that the desired allowance for trimming may be made in clipping the stock.

In its more subordinate nature, the invention also embodies those novel details of construction, combination and arrangement of parts, all of which will be first described and then be specifically pointed out in the appended claims, and illustrated in the accompanying drawings, in which:

Figure 1, is a perspective view illustrating the application of my invention. Fig. 2, is a similar view of my invention, a part of the table structure being removed. Fig. 3, is an enlarged detail perspective view of one of the butting blocks, showing its connection with the gage bar. Fig. 4, is a cross section on the line 4—4 of Fig. 3. Fig. 5, is an enlarged detail plan view of one end of the gage carrying bar showing the provisions for adjusting the gage or scale to allow for trimming. Fig. 6, is a detail central vertical longitudinal section of a part of the invention. Fig. 7, is a detail view of a gage bar. Fig. 8, is a top plan view of the device.

Referring now to the accompanying drawings, in which like letters and numerals of reference indicate like parts in all of the figures, 1 designates a table having slats 2, certain of which 3—3 are made of metal and are supported on standards 4 and brackets 5. The brackets 5 are fastened at 6 to the front beam 7 of the table 1, while the standards 4 rest on the floor. Each standard 4 and bracket 5 carries a sprocket wheel 8 and 9,

respectively, while an endless chain 10 takes around each pair of sprocket wheels 8 and 9. Each chain 10 engages a drive sprocket 11-11 on a shaft 12 that is journaled in 5 bearings 13. A fixed ratchet wheel 14 is secured to the table 1 and has an aperture to form one of the bearings 13 for the shaft 12. A hand wheel 15 is secured to the shaft and has a handle 16 pressed by a spring 17 10 into normal engagement with the ratchet face 18 of the ratchet wheel 14 to hold the shaft in its various positions.

A carriage or butting block 19 rides on each bar 3 and is secured at 20 to the respective chain 10, so that both carriages 19 will be moved in unison by such chains as the shaft 12 is turned. Each carriage 19 has a knee or block 21 at its front end to abut the veneer strip 30 as it is projected onto the 20 table 1 from the clipper 31.

One (or both) of the bars 3 is provided with a dove-tail groove 22 in its upper face in which a gage bar 23 is removably held by a set screw 24 that passes through a slot 25 in the gage bar 23 and enters the bar 3. The gage bar 23, shown in detail in Fig. 7, forms one of the primary features of my invention in that while the scale is graduated in feet, inches and fractions of inches the shrinkage 25 30 allowance has been added thereto. For example, if the operator is cutting wood that shrinks 8 per cent. of its width in drying he uses a gage 23 calibrated on that percentage, so that if a cutting order calls for a width 35 of veneer, say, 23 inches wide (dry) the operator sets his block at the mark indicating 23 inches and clips the veneer; in reality the strip clipped is 25 inches wide when 40 clipped, but as it shrinks 8 per cent. in drying it comes out the required width of 23 inches when ready for delivery. The gage bars 23 are made removable so that a gage bar for any kind or texture of wood may be used since different woods have different 45 coefficients of shrinkage, and therefore a gage having its scale graduated to allow for shrinkage intended for use in connection with oak wood, would be unsuitable for use in connection with maple and a separate 50 scale must be used therefor.

Sometimes stock must be trimmed after drying and in order to make allowance therefor I provide the slot 25, which in practice is about $1\frac{1}{2}$ inches long and the gage bar 23 55 may be provided with a supplemental scale 26 graduated in pure inches and fractions of inches to coöperate with an indicating mark 27 on the bar 3 for convenience in setting the scale. Thus if the operator desires to allow $\frac{3}{4}$ of an inch in width in trimming he loosens the set screw 24 and moves the gage bar 23 until the mark corresponding to $\frac{3}{4}$ inch on the supplemental scale 26 registers 60 with the indicator mark 27 and tightens the screw 24 so that each piece of stock when

cut will not only carry the shrinkage allowance but also the $\frac{3}{4}$ of an inch trimming allowance.

Gages figured on different percentages of shrinkages may be made so as to apply to all the different kinds and texture of wood and by constructing the bar 3 and gage 23 as described, the gages 23 may be interchanged with great rapidity and as frequently as desired. On the side of the part 3 is a 75 series of holes 28 drilled closely together to receive pins or pegs 29, so that if the operator is clipping for two widths, but has occasion to shift his blocks for other widths as the condition and defects in the stock may 80 compel, and if he is cutting, say, 6 inches and 15 inches stock, he puts a peg 29 into the hole in front of the block at 6 inches, slides the block back to 15 inches and places a peg behind it so that he can shift the block 85 forward to 6 inches or back to 15 inches without even looking at the table.

In the practical application of my invention the table 1 is moved up into engagement with the veneer clipper 31, (which clipper 90 may be of any approved type, as the same, *per se*, forms no part of my present invention) to receive the veneer 30 as it passes under the clipper knife onto the table 1 and the carriage blocks 19 being set to the desired position, the stock will cease moving as it engages such blocks and the operator may then set the clipper into motion to clip the section of the veneer strip to the size desired, after which said strip may be removed and a second section clipped in a similar manner.

From the foregoing description taken in connection with the accompanying drawings, it is thought the complete construction, operation and advantages of my invention will be readily understood by those skilled in the art to which the invention appertains.

What I claim is:

1. As a new article of manufacture, a gage table for clipping machines comprising a support separate from the clipping machine, a bar mounted on said support, a carriage slideable on said bar, and means for moving said carriage from place to place along said bar.

2. As a new article of manufacture, a gage table for clipping machines comprising a support separate from said clipping machine, a bar mounted thereon, a carriage slideable on said bar, means for moving said carriage from place to place along said bar, and means for holding said carriage in its various positions.

3. As a new article of manufacture, a gage table for clipping machines comprising a supporting frame separate from the clipping machine, a pair of bars mounted thereover, a carriage mounted on each of

said bars, means operatively connecting said carriages together to move in unison, and means forming a coöperative part of said last named means for moving said carriages 5 along said bars.

4. As a new article of manufacture, a gage table for clipping machines comprising a supporting frame separate from that of the clipping machine, a pair of bars

10 mounted thereover, a carriage mounted on each of said bars, means operatively connecting said carriages together to move in unison, means forming a coöperative part of said last named means for moving said car-

15riages along said bars, said bars having recesses in one face, and gage bars held in said recesses with the exposed faces of said gage bars flush with those of the respective bars in which said gage bars are mounted.

20 5. As a new article of manufacture, a gage table for clipping machines comprising a supporting frame separate from that of the clipping machine, a pair of bars mounted thereover, a carriage mounted on each of

25 said bars, means operatively connecting said carriages together to move in unison, means forming an operative part of said last named means for moving said carriages along said bars, said bars having recesses in one

30 face, and gage bars removably held in said recesses with the exposed faces of said gage bars substantially flush with those of the respective bars in which said gage bars are mounted.

35 6. As a new article of manufacture, a gage table for clipping machines comprising a supporting frame separate from that of the clipping machine, a pair of bars mounted thereover, a carriage mounted on each of

40 said bars, means operatively connecting said carriages together to move in unison, means forming a coöperative part of said last named means for moving said carriages along said bars, one of said bars having a recess in one face, a gage bar held in said

45 recess, and means for adjustably holding said gage bar in said bars.

7. As a new article of manufacture, a gage table for clipping machines comprising a

50 supporting frame separate from that of the clipping machine, a pair of bars, mounted thereover, a carriage mounted on each of said bars, means operatively connecting said

55 carriages together to move in unison, means forming a coöperative part of said last named means for moving said carriages along said bars, said bars having a recess in one face, a gage bar removably held in said

60 recess, and means for adjustably holding said gage bars in said bars.

8. As a new article of manufacture, a gage table for clipping machines comprising a supporting frame separate from that of the clipping machine, a pair of bars mounted

65 thereover, a carriage mounted on each of

said bars, means operatively connecting said carriages together to move in unison, means forming a coöperative part of said last named means for moving said carriages along said bars, said bars having a recess in 70 one face, a gage bar held in said recess, said gage bar having a scale graduated with shrinkage allowance.

9. As a new article of manufacture, a gage table for clipping machines comprising a 75 supporting frame separate from that of the clipping machine, a pair of bars mounted thereover, a carriage mounted on each of said bars, means for coöperatively connecting said carriages together to move in unison, means forming a coöperative part of said last named means for moving said carriages along said bars, said bars having recesses in one face, and a gage bar removably held in said recesses, said gage bar having a 80 scale graduated with shrinkage allowance.

10. As a new article of manufacture, a gage table for clipping machines comprising a supporting frame separate from that of the clipping machine, a pair of bars mounted thereover, a carriage mounted on each of said bars, means operatively connecting said carriages together to move in unison, means forming a coöperative part of said last named means for moving said carriages 85 along said bars, one of said bars having a recess in one face, a gage bar held in said recess, said gage bar having a scale graduated with shrinkage allowance.

11. As a new article of manufacture, a 100 gage table for clipping machines comprising a supporting frame separate from that of the clipping machine, a pair of bars mounted thereover, a carriage mounted on each of said bars, means operatively connecting said 105 carriages together to move in unison, means forming a coöperative part of said last named means for moving said carriages along said bars, at least one of said bars having recesses in one face, gage bars held 110 in said recesses, and means for adjustably holding said gage bars in said bars, said gage bars having a scale graduated with shrinkage allowance.

12. In a gage table, a bar having a groove 115 in one face, a carriage slidable on said bar, a gage bar held in said groove and interengaged with said bar and having a scale graduated thereon with shrinkage allowance and having a supplemental scale graduated 120 on said bar to coöperate with said first mentioned scale in addition thereto and means for securing said bar from movement in said groove.

13. In a gage table, a bar having a groove 125 in one face, a carriage slidable on said bar, a gage bar held in said groove and interengaged with said bar and having a scale graduated thereon with shrinkage allowance and having a supplemental scale graduated thereon 130

in addition thereto, said grooved bar having an indicating point coöperating with said supplemental scale whereby said gage bar may be adjusted in its groove said gage bar having a slot adjacent to said supplemental scale, a bolt passing through said slot to secure said gage bar from movement.

14. As a new article of manufacture, a gage table for clipping machines comprising a supporting frame separate from that of the clipping machine, a pair of bars mounted thereover, carriages slidable on said bars, endless chains connected with said carriages, a drive shaft, connections between said drive shaft and said endless chains whereby when the drive shaft is turned said carriages will be moved in unison along their respective bars and means by virtue of which said shaft may be turned.

15. As a new article of manufacture, a gage table for clipping machines comprising a supporting frame separate from that of the clipping machine, a pair of bars mounted thereover, carriages slidable on said bars, endless chains connected with said carriages, a drive shaft, connections between said drive shaft and said endless chains whereby when the drive shaft is turned said carriages will be moved in unison along their respective bars, means by virtue of which said shaft may be turned, said last named means including a hand wheel, and means coöperating with said hand wheel for locking said shaft from operation.

16. In a gage table, a supporting frame, a pair of bars mounted thereover, carriages slidable on said bars, endless chains connected with said carriages, a drive shaft, connections between the drive shaft and said endless chains whereby when the drive shaft is turned said carriages will be moved in unison along their respective bars, means by virtue of which said shaft may be turned, one of said bars having a series of pin receiving apertures, and pins adapted to be inserted in said apertures to form stops for one of said carriages.

17. In a gage table, a supporting frame, a pair of bars mounted thereover, carriages slidable on said bars, endless chains connected with said carriages, a drive shaft, connections between said drive shaft and said endless chains whereby when the drive shaft is turned said carriages will be moved in unison along their respective bars, means by virtue of which said shaft may be turned, means for locking said shaft from operation, one of said bars having a series of pin receiving apertures, and pins adapted to be inserted in said apertures to form stops for one of said carriages.

18. In a gage table, a supporting frame, a bar mounted thereover, a carriage slidably

supported on said bar and forming an abutment, and a scale carried by said bar having 65 graduations divided into feet, inches and fractions thereof with shrinkage allowance said bar having a supplemental set of graduations in feet, inches and fractions thereof, and indicator marks on said bar for said 70 first mentioned and supplemental graduations, and means for securing said scale to said bar in its various positions.

19. As a new article of manufacture, a gage table for clipping machines comprising 75 a supporting frame including standards, said frame adapted to be moved into contact with a clipping machine, a plurality of bars fixedly secured to said frame, a sliding carriage on each bar, an endless chain mechanism for each carriage for moving the same, a common operating shaft geared with each 80 of said chain mechanisms for turning said shaft, and means coöperating with said turning means for locking said shaft from 85 movement.

20. As a new article of manufacture, a gage table for clipping machines comprising a supporting frame including standards said frame adapted to be moved into contact 90 with a clipping machine, a plurality of bars fixedly secured to said frame, a sliding carriage on each bar, an endless chain mechanism for each carriage for moving the same, a common operating shaft geared with each 95 of said chain mechanisms for turning said shaft, means coöperating with said turning means for locking said shaft from movement, each of said bars having a longitudinal dove-tail groove in one surface and a 100 dove-tail gage bar mounted in said groove, said gage bar having suitable graduations, said gage bar having a slot, and means passing through said slot for securing said gage bar in different positions in said groove to 105 the respective grooved bar.

21. As a new article of manufacture, a gage table for clipping machines comprising a supporting frame including standards, said frame adapted to be moved into contact 110 with a clipping machine, a plurality of bars fixedly secured to said frame, a sliding carriage on each bar, an endless chain mechanism for each carriage for moving the same, a common operating shaft geared with each 115 of said chain mechanisms for turning said shaft, means coöperating with said turning means for locking said shaft from movement, and means carried by said bars for limiting the movement of said carriages on 120 said bars between certain limits.
